UNITED STATES PATENT OFFICE.

ROY A. RIDDLE, OF NEW ORLEANS, LOUISIANA, AND WARD D. CARPENTER, OF MEMPHIS, TENNESSEE, ASSIGNEES TO STANDARD OIL DEVELOPMENT COMPANY, A CORPORATION OF DELAWARE.

FLUID-PRESSURE-OPERATED HOIST.

Application filed July 25, 1924. Serial No. 728,096.

This invention relates to improvements in vehicle elevating means operated by fluid pressure. The primary purpose of the invention is to provide a simple, easily operated device adapted to raise an automobile or other vehicle into a position facilitating lubrication, repairs and the like.

Fluid-pressure-operated hoists for automobiles have heretofore been devised and 10 have been found to present important advantages over hoists operated by screw jacks, cable and drum means, crank and gear connections and equivalent mechanical devices. Experience has shown, however, that prior 15 fluid-pressure-operated hoists in some respects lack the simplicity and flexibility which are essential for general commercial use.

In accordance with the present invention 20 there is provided a hoist characterized by certain important advantages new in the art. Among these may be mentioned the provision of a simple, strong frame adapted for easy actuation by hydraulic lifting means or 25 the like, and the combination with such frame of improved auxiliary supporting means for insuring the safe use of the hoist. A particular advantage of the new construction is that it may be elevated bodily in 30 horizontal position or may be tilted upward at either end.

Other objects and advantages of the invention will be apparent from the appended description taken in connection with the accompanying drawing in which—

Fig. 1 is a side elevation of a preferred embodiment of the improved hoist installation, partly in section to show the construction of the fluid pressure means;

Fig. 2 is a top-plan view of the hoist; and

Fig. 3 is an enlarged detail showing the manner of connecting the frame to its supporting means.

Referring to the drawing, reference numerals 1 and 2 denote suitable frame members for receiving the wheels of the vehicle. Channel irons are preferably used for this purpose. If desired the frame may be so arranged as to engage the axles of the vehicle but it is ordinarily more convenient to provide track-like members upon which the vehicle may be run or drawn. The channel irons or equivalent means are rigidly con-

nected together by crossbars 3 and 4. The frame so formed is supported upon beams 5 and 6 which are firmly secured by means of rivets or the like respectively to the tops of pistons 7 and 8.

The frame is prevented from moving laterally by flanges or blocks 9 secured to the beams 5 and 6. It may however have a slight longitudinal motion limited by flanges 10 and 11 riveted to the under side of the beams. Chains 12 may be secured to the beams 5 and 6 and to the frame: their primary purpose is to prevent substantial vertical displacement of the frame while allowing it some freedom of movement to permit tilting, as subsequently described. I-beams are preferably used. They should have the margins of their upper flanges bent downwardly, as shown most clearly in Fig. 3, to facilitate the tilting movement of the frame.

To guard against settling of the frame in case of a fall of pressure in the lifting means, legs 13 are pivoted to the frame at 14. These legs are held against the channel irons by suitable catches 13^a when not required for use.

In a preferred embodiment of the lifting means, a pressure-resisting tank 15 containing oil 16 is connected through pipe 17 to an air-compressor or other sources of fluid pressure (not shown). A pipe 18 has its lower end submerged in the oil and leads 85 through two branches 19 and 20 respectively to cylinders 21 and 22 in which the pistons 7 and 8 operate. The opening through which the oil enters each piston is preferably of restricted area so that in case of 90 fall of pressure the oil can not escape rapidly.

The pistons, one of which is shown in section in Fig. 1, have a loose sliding fit in the cylinders. The oil or other fluid passes 95 downwardly between the cylinder and piston to the chamber beneath the latter. The pistons should be of sufficient length to permit adequate elevation of the frame while leaving a considerable portion of the piston within the cylinder. In this way the stability 100 of the frame and its burden is insured. The upward travel of the piston is preferably restricted by a band 23 secured to it at a suitable point. It is convenient to shrink a band 105 on the piston at a point such that it will

meet a shoulder at the head of the cylinder when the maximum desired elevation is reached.

I have found that it is ordinarily satisfactory to employ only a single elevating device at each end of the frame but two or more may be used at each end, if desired. Other than terminal arrangements of the elevating means are feasible also.

10 When the improved device is installed in the open air it is desirable to provide drain pipes 24 or the like for taking off surface water.

In the operation of the hoist, the automobile or the like to be given attention is run upon the frame in lowered position. The air pressure is then turned on, forcing oil into the cylinders 21 and 22 from the oil supply tank 15. When the frame has reached its 20 upper position, the air-line is closed by actuation of a three-way valve 25 and the supporting legs on the frame are let down. Chocks 26 secured by chains 27 may be provided to prevent the automobile from rolling off the 25 frame. It is convenient to provide rack bars 28 on the sides of the frame for adjustably receiving the chains that secure the chocks.

As noted above, an important novel feature of the present invention is the adaptability of the hoist to either horizontal or oblique lifting. Valves 29 and 30 in the oil lines are provided so that either line may be cut off as desired when only one end of the frame is to be elevated. When the supporting legs are raised and the pressure released 35 by suitable actuation of the valve 25, the

frame will settle slowly into its lowermost position as its weight displaces the oil from the cylinders.

While reference has been made particularly to the use of oil as a pressure-transmitting fluid, it will be understood that any suitable fluid-pressure means is applicable. Pneumatic or hydraulic devices of various types may be used. While at present I regard a 40 stationary installation designed for facilitating lubrication and repair of automobiles as a preferred embodiment of the invention, portable units may be provided and used for different purposes, such as the handling of 45 cars for shipment or storage. Various other modifications of the illustrative form of the invention described may be made within the scope of the appended claim.

50 We claim:

A hoist comprising longitudinal members 60 adapted to receive a vehicle, fluid-pressure means beneath said members and operably disposed to elevate the same, transverse I-beams having an upper flange bent downwardly to provide a curved surface and supporting said members for longitudinal tilting movement, stops at each end of said members for limiting such movement, stops 65 for preventing transverse movement of such members, and means for preventing substantial vertical movement of said members with respect to said beams while permitting tilting of said members.
